Primary Examiner — Cathron C Brooks*Assistant Examiner* — Christian P. McLean(74) *Attorney, Agent, or Firm* — David R. Stevens; Stevens Law Group(57) **CLAIM**

The ornamental design for a bottle, as shown and described.

DESCRIPTION

FIG. 1 is a perspective view of the bottle of this design.

FIG. 2 is a front view of the bottle of FIG. 1.

FIG. 3 is a back view of the bottle of FIG. 1.

FIG. 4 is a top view of the bottle of FIG. 1.

FIG. 5 is a bottom view of the bottle of FIG. 1.

FIG. 6 is a right side view of the bottle of FIG. 1; and, FIG. 7 is a left side view of the bottle of FIG. 1.

The broken lines illustrate portions of the bottle that form no part of the claimed design.

The article in which the design is embodied is for use in storing consumable liquids.

1 Claim, 5 Drawing Sheets(56)
